SHIP

Edward V. Lewis, Hohokus, N.J., assignor, by mesne assignments, to the United States of America as represented by the Secretary of the Navy

Filed Mar. 11, 1959, Ser. No. 798,795

5 Claims. (Cl. 114—56)

This invention generally relates to surface ships for high speed operation, and more particularly relates to improvements in hulls for surface ships in order to obtain greater seaworthiness at high speeds in rough waters.

A surface ship undergoes various undesirable motions, such as roll, pitch, and heave, when traveling in seaways. When these motions are excessive, they produce destructive forces which have an adverse effect on the structure of the ship's hull, on the structural parts and arrangements within the hull, and on the functioning of machinery, instruments and other equipment of the ship. In the case of a fully loaded cargo ship, excessive motions may cause shipping of water in head seas to the detriment of the ship's cargo. Furthermore, accelerations inherent in such motions are believed to be primarily responsible for seasickness and frequently for shipboard accidents. Other undesirable effects are caused by motions of a ship; and it is not unusual for a ship to reduce its speed in order to limit such effects.

The nature and extent of the motions of a surface ship depend in part upon the waves that the ship encounters. The waves will be of different lengths, heights and steepness, and include waves having lengths of the same order of magnitude as the length of the ship. Under certain conditions of ship's speed, a "synchronism" arises which magnifies some of the motions of a ship and increases the harmful effects thereof. This synchronism arises when the natural pitching period of a ship harmonizes with its period of encounter with waves. The speed of a ship, when this synchronism arises, is called the critical speed of the ship. When the speed of the ship is below this critical speed, it is recognized as operating in a subcritical range, and when above in a supercritical range. Operating the ship in either range reduces the deleterious effects of the magnified motions of synchronism.

An object of the invention is to provide a displacement-type surface ship capable of operating safely and with small amplitudes of vertical motions at high speeds in both calm and rough seas, the ship being capable of operating at supercritical speeds in rough seas when such operation is preferred.

It is a further object of the present invention to provide lines for the hull of a ship that result in a ship having reduced amplitudes of motion, and comparatively higher safe operating speeds, especially in rough seas, and other advantages.

In general, it is an object of the invention to provide a surface ship of high speed having a long natural pitching period.

Other objects and many of the attendant advantages of this invention will be readily appreciated as the same becomes better understood by reference to the following detailed description when considered in connection with the accompanying drawings in which like reference nu-

2

merals designate like parts throughout the figures thereof and wherein:

Figs. 1A and 1B, joined along the broken lines, is a longitudinal elevational outline view of a ship having a hull in accordance with the invention;

Figs. 2A and 2B, joined along the broken line, is a diagram showing, in accordance with standard practice, a half-plan view of the longitudinal water lines of the hull at different water line planar levels;

10 Fig. 3 is a diagram showing, in accordance with standard practice, a body plan of the transverse hull lines or cross-sections at various stations, the lines on the right of the center line being forward or forebody lines at different stations, and the lines on the left of the center line being the aft or afterbody lines at different stations.

A ship in accordance with the invention is built with a hull along the lines of Figs. 1-3. Figs. 1A and 1B, the top line A represents the main deck and the bottom line B represents the base line of the hull, and may be considered indicative of its keel. The ship has a bow C and the stern D. In Figs. 2A and 2B the line E represents the vertical longitudinal center plane of the hull, it being understood that the hull is symmetrical on both sides of this plane.

25 For identification purposes, the length of the ship is divided into spaced transverse stations. Generally the practice is to divide the ship into twenty stations, each station representing a plane that is perpendicular to the longitudinal axis of the hull. The stations shown in Figs. 30 2A and 2B are the even stations 0(zero) through 20, but with the addition of a central station 11. The stations are equally spaced except that stations 10 and 11 and stations 11 and 12 have somewhat smaller spaces therebetween, the two spaces, however, being equal.

35 Similarly, as shown in Fig. 3, the vertical extent of the hull is divided by spaced horizontal water line planes shown as lines (WLP) 2, 4, 6, 8, 12, 13, 14, 16, 17, 18, 20, 22 and 24 which are relatively spaced from the base line in the ratios indicated in the associated parentheses.

40 The figures are drawn substantially to scale, but not necessarily to the same scale. In Figs. 1A and 1B, the vertical scale is double the horizontal (fore and aft) scale. In Figs. 2A and 2B, the vertical scale is three times the horizontal scale. This has been done in order better to 45 show the configuration of the water line projections which, if drawn to the same scale throughout, would require the lines to be more closely spaced than shown in the figure. In Fig. 3, the horizontal and vertical scales are the same.

50 The transverse station planes and the water line planes intersect the hull in curved lines which are indicated in Figs. 2A, 2B and 3 in accordance with standard practice, each line being identified with the plane in which it lies. In Figs. 2A and 2B these curved lines are the lines including the designation WL; and in Fig. 3 they are the lines including the designation T.

An inspection of Figs. 2A, 2B, and 3 shows that the hull forms a long slender ship with very fine water lines that is adapted for destroyer type vessels. The ship shown has a length to beam ratio of 10.5.

It is difficult to describe the shape of the hull in a few words. As indicated in Figs. 2A and 2B, between the transverse central stations 10 and 12, which may be called the midship of the hull, the hull is of fairly uniform width, except at the bilge and below the water line. The distance between stations 10 and 12 represents 13.3 percent of the length of the ship. The distance forward

of station 10 to the zero station represents 48.2 percent of the length of the ship.

Forwardly of station 10, the water lines converge longitudinally fairly smoothly to the bow stem, but with the upper and the lowermost lines somewhat more rapidly than the central longitudinal lines WL4 through WL13. Rearwardly or aft of station 12, the bottom rises relatively rapidly to a knuckle near water line plane WLP10. The upper abaft water lines converge longitudinally and more rapidly than the forward water lines.

Transversely, the upper midship portion between stations 10 and 12 has fairly straight walls with slight tumble home near the top. Fore and aft of midship portion, the hull has significant tumble home. This is apparent from Figs. 2 and 3. The water line plane WLP13 forms the water line of the ship under normal operation. This line is only slightly above the vertical center water line plane of the hull which is exactly midway between the deck and base line; and the tumble home above WLP13 is appreciable both fore and aft of the midship portion. This is apparent in Fig. 3 from the large inward curving of lines T2, T4, T6 and T8 of the morebody, and lines T14, T16, T18 and T20 of the afterbody. The inward curvature of these lines starts from below WLP13, the normal water line plane, and extends almost to the deck, WLP24.

As is apparent from Figs. 2A, 2B and 3, the hull is shaped somewhat like a submarine, except for the uppermost part which is bounded by the main deck at the water line plane WLP24. The reason for this is to permit the ship to ride lower in the water when it encounters rough seas. Water line plane WLP17, called the submerging water line plane for convenience, represents the water line for the ship operating in such seas. This last line is about three-fourths of the height of the hull above the base line. When riding thus, the ship resembles a surfaced submarine but is considerably longer and more slender.

In order to lower the ship to the submerging water line plane, thereby increasing the displacement, the ship is provided with peak water ballast tanks fore and aft, and with flooding and pumping equipment to fill and empty the tanks. Preferably the heavier moving parts of this equipment are in the midsection of the ship. The tanks and equipment, per se, form no part of the invention, since any suitable apparatus may be used. Accordingly, they have been schematically indicated in Figs. 1A and 1B as comprising tanks 50 and 52, and pumping equipment 54.

It will be observed in Figs. 2A and 2B that the ship has a narrow main deck indicated by water line WL24, and that the submerging water line area encompassed by the WL17 is also narrow but not as narrow as the deck. The ship has a low freeboard above the water line plane 17.

In calm weather, the ship floats at the normal water line shown. Under storm conditions, the ballast tanks are filled until the ship settles so as to be at the higher submerging water line. The result is an increase in the natural pitching period of the ship arising from the increased mass, radius of gyration, and decreased water-plane area. The location of the ballast at the peaks of the hull also lengthens the natural pitching period.

The increased pitching period of the ship induces the ship to plunge through waves rather than riding over them. The ship can then operate at supercritical speeds with acceptable seaworthiness. A lengthened and fine ship of a type described with lengthened pitching period permits operation in storm seas at speeds as much as fifty percent higher than ships of customary design such as the aforesaid destroyer.

The high speed operation in rough seas and the low freeboard subject the ship to boarding seas. Consequently, the ship must be structurally strong, with the main deck heavily built. The size of the structure above the

deck, represented by numeral 56 in Figs. 1A and 1B, is kept to a minimum, with adequate strength to withstand the boarding water.

Because of the rounded sides of the ship, it is prone to rolling motion. For reduction of this motion, antirolling fins may be provided on the hull.

The improved characteristics of a ship in accordance with the invention is apparent from the following data given in unit ratios unless otherwise indicated.

	Semi-submerged Ship at deep draft	Destroyer (WLP17)
Length of LWL	5.720	5.720
Breadth	0.608	0.540
Draft	0.208	0.250
Displacement, pound units	24.5	27.7
Freeboard at bow, F	0.280	0.100
Freeboard ratio, F/L (Length)	0.049	0.017
Longitudinal radius of gyration	0.24L	0.26L
Natural pitching period, T_p , sec	0.60	0.92
$T_p / \sqrt{L}$	0.25	0.38

Obviously many modifications and variations of the present invention are possible in the light of the above teachings. It is therefore to be understood that within the scope of the appended claims, the invention may be practiced otherwise than as specifically described.

I claim:

1. A surface ship adapted for high speed operation in rough seas while traveling in a semi-submerged condition, comprising a hull having a normal operation water line substantially midway of the height thereof, said hull having a midship portion with substantially straight sides above said water line, the portion of said hull forward of said midship portion having a deck having a lesser area than the area of a plane through said water line, the portion of said hull forward of said midship portion being longer than the portion of said hull aft of said midship portion, said forward and said aft portions having tumble home lines, the forward portion comprising about 48.2 percent of the ship's length, and the midship portion about 13.3 percent of the ship's length, said forward portion converging to the bow stem, and said rearward portion converging to a knuckle line at the stern, the bottom, exterior of said hull being outwardly curved from said water line to its keel, said ship having peak ballast tanks adapted when filled to place the water line a distance about three-fourths of the height of the hull above its base line, a plane through the last said waterline being of lesser area than the area of the plane through the first said water line, but of greater area than said deck.

2. A surface ship adapted for high speed operation in rough seas while traveling in a semi-submerged condition, as set forth in claim 1 wherein the forward portion of said hull between said first and second water lines is outwardly curved at the exterior surface thereof.

3. A surface ship adapted for high speed operation in rough seas while traveling in a semi-submerged condition, as set forth in claim 1 wherein, the portion of said hull aft of said midship portion lying between the first and second water lines is outwardly curved at the exterior surface thereof over at least a portion of the area thereof.

4. A surface ship adapted for high speed operation in rough seas while traveling in a semi-submerged condition, as set forth in claim 1 wherein, the exterior surface of said hull both forward and aft of the midship portion, and above said second waterline, is inwardly curved.

5. A surface ship adapted for high speed operation in rough seas while traveling in a semi-submerged condition, as set forth in claim 1 wherein, the exterior surface of the forward portion of the hull located between the first and second waterlines is composed at least in part, of an area that is outwardly curved at the exterior surface, and a portion that is inwardly curved at said exterior surface,

and is inwardly curved above said second waterline; and the portion of said hull aft of said miship portion and located between said first and second waterlines has substantially the entire exterior surface thereof outwardly curved, and said exterior surface of said aft portion of the hull located above said second waterline inwardly curved.
